UNITED STATES PATENT OFFICE.

ALBERT E. LANE, OF CHICAGO, AND JOSEPH R. BLAINE AND CARL HENDERSON, OF OAK PARK, ILLINOIS, ASSIGNEES TO MIEHLE PRINTING PRESS & MANUFACTURING COMPANY, OF CHICAGO, ILLINOIS, A CORPORATION OF ILLINOIS.

SHEET-BUCKLER.

1,289,051.

Specification of Letters Patent. Patented Dec. 24, 1918.

Application filed January 15, 1917. Serial No. 142,522.

To all whom it may concern:

Be it known that we, ALBERT E. LANE, JOSEPH R. BLAINE, and CARL HENDERSON, citizens of the United States, residing at 5 Chicago and Oak Park, in the county of Cook and State of Illinois, have invented certain new and useful Improvements in Sheet-Bucklers, of which the following is a specification.

10 The invention relates to improved means for segregating sheets individually from a pile for delivery by suitable feeding mechanism to a printing couple.

15 Many devices have been resorted to for effecting such segregation, including buckling, combing and lifting mechanism.

An objectionable feature found in varying degree in most devices of the combing and buckling type is the tendency to rub the 20 sheet, smearing the undried ink from a former printing operation or so unfavorably affecting the surface of the papers as to prevent its taking the ink properly.

Where lifting devices have been employed, 25 whether operated mechanically or pneumatically, it has been found that there is such a lack of certainty in operation due to the occasional missing of a sheet, or more seriously, the lifting of two sheets at once, 30 that devices of this type fall far short of being satisfactory in modern commercial practice wherein speed and accuracy is of so great importance.

According to our invention we have entirely eliminated frictional or rubbing contact between the sheets to be separated and the underlying pile by doing away with the 35 combing or buckling as previously practised and have avoided the uncertainties of the known lifting devices by the utilization 40 of the pneumatic lift in combination with the buckling feature, whereby the advantages of the pneumatic lift are reinforced by the certainty in operation of the buckling of the sheet to effect accuracy in sheet separation.

This is accomplished by employing pneumatic suckers to engage the sheet and lift it 45 free of the underlying pile and to hold the same slightly above the pile, and then to buckle the sheet while so held and in such manner as to insure individual separation and yet not to rub against the next sheet of the pile, this by reason of the fact that the

suckers have no lateral movement relative 55 to the lifted sheet nor relative to the underlying sheet in the act of buckling until after the lifting of the sheet clear of the pile.

In order that the invention may be readily understood in the principle of its operation by those skilled in the art, one practical embodiment of the same is set forth in the accompanying drawings and in the following detailed description. Obviously the invention is susceptible of embodiment in other 60 and varied constructional forms without departure from the essence thereof and it is to be understood, therefore, that the drawing and description are to be considered as 65 illustrative and not as unnecessarily limiting the invention. In these drawings,

Figure 1 is a fragmentary side elevational view illustrating a pneumatic sheet buckling device embodying the invention;

Fig. 2 is a front elevation of the parts 75 shown in Fig. 1;

Fig. 3 is a horizontal section taken substantially on the line 3—3 of Fig. 1;

Figs. 4 and 5 are detail sectional views 80 illustrating the operation of the invention, the same being taken substantially on the lines 4—4 and 5—5 of Fig. 3.

Figs. 6 and 7 are diagrammatic views 85 illustrating steps intermediate those represented by Figs. 4 and 5; and

Figs. 8, 9 and 10 illustrate the successive steps to the same end as carried out by a slightly modified form of construction.

As illustrated, the pile table is indicated at 11, the pile of sheets at 12, and above the 90 same the sheet segregating mechanism forming the subject matter of the present invention in operative relation to the sheet at the feeding end of the press.

Suitably connected with appropriate 95 sources of air under pressure, not shown, are the blowers 13 and 14 whereby the corner of the pile of sheets is subjected to a blast at intermittent periods for the purpose of ruffling the corners of the sheets as is commonly practised and as indicated in Fig. 4 at 15. At 16 is represented a presser foot for holding down the underlying sheet while the one sheet is being removed, this foot being in the nature of a nozzle likewise supplied through the pipe 17 with air under pressure for the purpose of more effectually separating the sheet throughout its length 105

and breadth while being fed from the pile to the press after segregation.

Upon the shafts 18 and 19, suitably supported and extending transversely of the feed board or pile table is mounted a yoke 20 with a lower horizontally projecting arm 21. The outer terminus of this arm is arranged as a guide for a slide 22 having a boss 23 serving as a journal in which is pivotally mounted by means of a pin 24 a sucker finger or shoe 25. This sucker shoe 25 is connected by means of the pipe 26 with a suitable exhaust whereby a partial vacuum may be intermittently created within the 15 shoe for lifting the corner of the sheet. A supplemental arm 27 is connected at 28 to the arm 21 and is apertured at 29 to accommodate a second sucker finger 30 forming the terminus of an exhaust pipe 31. This 20 sucker finger 30 is provided with two collars 32 and 33. Between the collar 33 and the arm 28 is disposed a compression spring 34, the action of said spring being to normally yieldingly hold the presser foot downward 25 against the restraining influence of the rod 35, the lower end of which takes under a pin 36 carried by the collar 32. The yoke 20 together with the arm 21 and the sucker shoe 25 with its connections, and also the 30 suction finger 30 are intermittently lifted bodily as the roller 37 rides upon the cam 38 mounted upon the constantly rotating shaft 18.

In a bifurcated ear 39 extending rearwardly from a pivotal connection with the pin 24 and pivotally connected thereto by a pin, is a bent rod 40 which is pinned at 41 to a block 42 clamped upon the lower end of an arm 43, which arm is attached by 40 means of a set screw 44 to a collar 45 loosely mounted upon the shaft 19, said collar having extending therefrom an arm 46 carrying a roll 47 which travels upon the cam 48 which is driven from the shaft 18. By 45 this means the slide 22 and the suction shoe 25 are intermittently reciprocated with reference to the arm 21 for a purpose which will be hereafter made clear.

Upon a rock shaft 49 and a fixed shaft 50 is guided a yoke 51 for vertical reciprocation. From the lower end of this yoke extends an arm 52 having hinged thereto by means of the pin 53 a block 54 within a split boss 55 of which there is adjustably mounted a stem 56 of a block 57 carrying the presser foot 16 with its hose or pipe connection 17. About the pin 53 is disposed a torsion spring 58 which serves to normally yieldingly hold the presser foot inwardly 55 to the right as shown in Fig. 1. From the block 54 extends inwardly a lug 59, and fixedly mounted upon the shaft 50 by means of the set screw 60 is a tappet 61 disposed above the lug 59.

The rock shaft 49 is intermittently ac-

tuated by means of a toothed sector 62 keyed upon said shaft and in mesh with a toothed sector arm 63 loosely mounted upon the shaft 19 and having an integral arm 64 carrying a roll 65 which rides upon the cam 70 66 which is mounted upon the rotating shaft 18. It will be readily understood that as the yoke 51 intermittently moves upward carrying with it the presser foot 16, the lug 59 engages the tappet 61 and thereby 75 swings the presser foot outwardly so as to clear the edge of the sheet lifted by means of the suction shoe 25 and suction finger 30 and thereafter as the yoke 51 descends the presser foot 16 swings inwardly beneath 80 the lifted sheet and above the pile 12 under the influence of the spring 53 so as to hold the top sheet of the pile down while the lifted sheet is removed and fed to the press.

A rod 67 fixedly mounted upon the shaft 35 50 has attached at its lower end a laterally extending spring 68 which overlies the corner of the pile and serves as an upper abutment to limit the upward lifting of the sheet when ruffled by means of a blast from the 90 nozzles 13 and 14.

The buckling of the sheets as carried out in that form of mechanism illustrated in Figs. 1 to 7 inclusive is as follows: The parts being in the position represented in Figs. 95 1 and 4, a blast of air is caused to issue from the nozzles 13 and 14 ruffling the sheets as shown in Fig. 4, the upward movement of the corners being limited by the spring 68.

A partial vacuum is then created in the 10 suction shoe 25 and suction finger 30, in the order named, the suction causing the upper sheet 12^a to be drawn into the concave mouth 25^a of the suction shoe and the tail of the sheet to tend downward. Simultaneously 105 with the application of the exhaust, the blast of air through 13 and 14 is intermittent, permitting the ruffled sheet corners other than 12^a to drop to their original position on the pile urged thereto by the downwardly extending tail of the lifted sheet as 110 represented in Fig. 6.

At this instant, the suction shoe 25 begins to move upward and toward the suction finger 30, thus causing the downward buckling of the sheet between said suckers, the downward buckled portion of the sheet and the downwardly extending tail of the sheet 115 pressing against the underlying sheets and assisting to restore them to a flat position 120 on the pile, this step being illustrated in Fig. 7 of the drawing.

Thereupon the suction shoe 25 continues to move toward the suction finger 30 and an upward movement is likewise transmitted thereto as the roll 37 rides upon the cam 38. The upward movement of the shoe 25 precedes the upward movement of the sucker finger 30 slightly, due to the space between the collar 32 and the arm 28 (Fig. 4) but 130

as soon as the arm 28 strikes the collar 12 they move upward together, lifting the sheet from the pile as shown in Fig. 5, and further accentuating the buckle of the sheet 5 at 12° as they continue to approach one another.

After the suctional engaging of the upper sheet by the shoe 25 or concurrently therewith the presser foot 16 moves upwardly and out clearing the upper sheet of paper to permit it to be buckled and lifted 10 and after the said paper is brought into position indicated in Fig. 5 the presser foot descends and moves inwardly upon the top 15 of the pile beneath the lifted sheet.

The sucker 25 now moves outwardly away from the sucker 30 straightening the buckled portion of the sheet to a certain extent above the presser foot, after which 20 an air blast is caused to emerge from the nozzle of the presser foot 16 and also from the nozzles 13 and 14 loosening the lifted sheet 12 from the pile throughout its length and breadth, it being understood that ordinarily 25 a mechanism the duplicate of that previously described acts upon a sheet at the opposite rear corner. The forward edge of the sheet is now grasped by the feeding mechanism for transportation to the press and as it moves forward suction is cut off 30 from the shoe 25 and finger 30 releasing the sheet for feeding to the press. The blast is then cut off from the presser foot 16 and the shoe 25 moves outward and downwardly 35 to engage the corner of the next sheet which is being ruffed by a blast from the nozzles 13 and 14 as indicated in Fig. 4 and previously described.

In Figs. 8, 9 and 10 are illustrated successive steps of separating the sheets by suction buckling as carried out by a slightly modified form of mechanism, characterized by the omission of the suction finger 30 or its equivalent, the entire action being carried out by the suction shoe 25.

As herein exemplified, the sheets having been ruffed at their corners as previously illustrated and described, the upper sheet is engaged by the concave mouth of the shoe 25 as suction is applied, the tail of the sheet corner, downwardly turned by the suction of the sheet into the concave face, serving to press downwardly on the ruffed sheet from which the blast has been removed 50 and tending to press the same into a flat position, this step being indicated in Fig. 8. The shoe 25 now moves upwardly and inwardly causing the sheet held stationary by its own weight and inertia to buckle 55 downwardly as indicated at 12° thus further pressing the upper sheet of the pile downward and serving to further insure against the lifting of two sheets by the segregating influence of the buckle as is well known in this art. This step is indicated in Fig. 9.

Hereupon, the presser foot having been removed as in the previous instance to clear the sheet and permit it to be lifted, is now again lowered and inserted upon the top of the pile beneath the sheet as indicated 70 in Fig. 10. Thereupon the suction shoe 25 again moves outwardly straightening the sheet to a certain extent above the presser foot. An air blast is now emitted from the presser foot 16 beneath the sheet and directed toward the center thereof so as to separate the same throughout its length and breadth from the underlying sheet, and as the sheet is grasped by the feeding mechanism the suction is cut off from the shoe 80 25 and the sheet released for feeding to the press.

We claim:

1. In a sheet buckler, suction means for lifting the marginal portion of the sheet 85 and for moving the lifted portion inwardly and buckling the same downward toward the sheet pile to effectually separate from the lifted sheet any underlying sheet clinging thereto.

2. In a sheet buckler, a sucker, means to apply suction thereto to lift the sheet marginally, and means to move the lifting sucker laterally and inwardly of the sheet to buckle the lifted sheet portion inwardly 95 of the said sucker to effectually separate from the lifted sheet any underlying sheet clinging thereto.

3. In a sheet buckler, a sucker having a mouth concave in cross-section, means to 100 apply suction thereto to lift the sheet, and means to move the lifting sucker laterally in line with said cross-section and toward the medial portion of the sheet whereby to buckle the sheet downwardly inwardly of 105 the said sucker to effectually separate from the lifted sheet any underlying sheet clinging thereto.

4. In a sheet buckler, a pair of suckers for engaging the sheet, means to apply suction intermittently thereto to lift the sheet from the pile, and means to move the suckers toward each other to buckle the sheet therebetween, whereby to effectually free the lifted sheet from an underlying sheet 110 clinging thereto.

5. In a sheet buckler, a pair of suckers for engaging the sheet, means to apply suction intermittently thereto to lift the sheet from the pile and thereafter to release the same, the said suckers arranged at unequal distances from the corner of the sheet, the outer sucker having a mouth concave in cross-section on a line extending between the two suckers, and means to move the 120 suckers toward each other to buckle the sheets downwardly therebetween whereby to effectually free the lifted sheet and underlying sheet clinging thereto.

6. In a sheet buckler, a sucker normally 130

disposed slightly above the surface of the pile near one corner thereof and having a mouth concave in cross section on a line extending toward the medial portion of the sheet, a presser foot arranged to overlie the pile inwardly of the sucker, pneumatic means for ruffling the corners of the sheet below the sucker, means to apply suction to the sucker to draw the sheet adjacent the corner into the concave mouth of the sucker and cause the tail corner of the sheet to tend downwardly against the underlying ruffled sheet, means to withdraw the presser foot after the engagement of the sheet by the sucker, means to move the sucker laterally toward the medial portion of the sheet to buckle the sheet downwardly to effectually separate from the lifted sheet any underlying sheet clinging thereto, means to move the sucker upwardly to lift the sheet corner farther in order to afford space thereunder, means to move the presser foot inwardly beneath the uplifted sheet and upon the top of the underlying pile, and means to direct a blast of air beneath the lifted sheet and above the pile whereby to separate the sheet from the pile throughout its length and breadth, the suction being arranged thereafter to be cut off to release the sheet as it is fed from the pile to the press.

7. In a sheet buckler, a sucker, means to apply suction thereto to first lift a portion of the sheet clear of the pile, and means

to next move the sucker laterally in one direction whereby to buckle the lifted sheet portion and effectually separate from the lifted sheet portion any underlying sheet clinging thereto and then to move the sucker laterally in the other direction whereby to straighten the sheet.

8. In a sheet buckler, a pair of suckers for engaging the sheet, means to apply suction intermittently thereto to lift the sheet from the pile and thereafter to release the same, the said suckers arranged at unequal distances from the corner of the sheet, the outer sucker having a mouth concave in cross-section on a line extending between the two suckers, and means to move the suckers toward each other to buckle the sheets downwardly therebetween whereby to effectually free the lifted sheet and underlying sheet clinging thereto and thereafter to move the suckers away from each other whereby to straighten the sheet.

In witness whereof we have hereunto signed our names in the presence of two subscribing witnesses.
